UNITED STATES PATENT OFFICE

EDWIN M. RAETZ AND JOHN EICHINGER, OF ROCHESTER, MINNESOTA

MEDICAMENT VAPORIZER

Application filed February 21, 1929. Serial No. 341,659.

This invention relates to an appliance which may be broadly entitled a medicament vaporizer, and it has more particular reference to a structure which is hereinafter more specifically referred to as an inhalant kettle.

More explicitly stated, the invention has particular reference to a portable domestic electrically operated appliance for vaporizing and producing medicated fumes such as

- 10 may be efficiently employed for the relief of inflammatory effects of the respiratory tract, as well as for the local application of heated vapors to the external portions of the body.
- 15 In carrying out the invention we have evolved and produced what we believe to be a novel contribution to this particular art, in that it embodies a structure which is characterized by unusual simplicity, durability and efficiency in operation and use.

Other features and advantages of the invention will become more readily apparent from the following description and drawings.

In the drawings:

- 25 Figure 1 is a top plan view of a medicament vaporizing kettle constructed in accordance with the invention.
- 30 Figure 2 is a side elevational view of the same.
- 35 Figure 3 is a vertical sectional view through the body portion.
- 40 Figure 4 is an enlarged front elevational view of the conoid nozzle.

In carrying out the invention we provide a receptacle or kettle 5 of appropriate proportions and materials. This is divided by a horizontal partition 6 into a lower compartment 7 and an upper compartment 8. The latter compartment is filled with the medicated fluid or other medicament employed. The partition 6 functions as a false bottom and is spaced upwardly from the supporting surface to prevent damage to the surface.

- 45 The reference character 9 designates a removable lid having a plurality of air circulating and vent holes 10. The reference character 11 designates generally an electric heater. This comprises a suitably wound resistance coil (not shown) confined with a seam-less metal housing or casing 12 of the configu-

ration shown. This embodies an outstanding supporting flange 13 carrying a casing 14 in which a thermostatically controlled switch (not shown) is arranged. The switch is confined within the compartment 7. The device 55 is electrically operated and current is supplied thereto from an ordinary house cord or cable 15 suitably connected with the thermostatic switch.

The fumes and hot vapors escape from the top of the kettle through the effluent spout 16. This extends upwardly at the appropriate angle and to a desired point where it terminates in a conoid or truncated conical discharge nozzle 17. This may be of a proportion to fit the nose and permit it to be inserted into it. It is flared at an appropriate angle to discharge the fume vapors uniformly into the room. As shown in Figure 4, there is a flange or lip 18 across the bottom of the nozzle and this defines what may be designated as a drain trough 19. Leading from this is a gravity drain pipe or tube 20 which returns the condensate to the spout. A suitable carrying bail 21 is provided with an appropriate insulated 65 hand grip 22.

The current supply cord is plugged into the wall socket, thereby setting the electric heating device 11 into operation. This being immersed in the medicament fluid, heats the 80 fluid by direct contact, air circulates through the openings in the lid and when the medicament is vaporized sufficiently the fumes and vapors rise through the spout and discharge through the nozzle.

It is thought that by considering the description in connection with the drawings a clear understanding of the construction, operation, features and advantages of the invention will be had. Therefore, a more lengthy 90 description will be regarded as unnecessary.

Minor changes in shape, size, materials and rearrangement of details coming within the field of invention claimed may be resorted to in actual practice if desired.

Having thus described the invention, what we claim as new and desire to secure by Letters Patent is:—

A vaporizer of the class described comprising a container contracted at its upper end, an 100

apertured closure for said upper end, an electrical heating element arranged in the container and including a casing extending vertically from the bottom of the container concentrically of the container, said heater casing having its upper end normally disposed above the normal level of the liquid in the container, the upper portions of the container providing a vapor chamber, a vapor discharge spout projecting at an incline from the top of said container, a substantially conical discharge nozzle on the upper end of said spout, said nozzle at the bottom thereof provided with a drain trough, and a gravity drain pipe connecting said trough with said spout.

15 In testimony whereof we affix our signatures.

EDWIN M. RAETZ.
JOHN EICHINGER.
